UNITED STATES PATENT OFFICE

2,489,205

AIR-CONDITIONING APPARATUS

Joseph H. Sweeney, Clarksville, Tenn.

Application March 15, 1945, Serial No. 582,885

1. Claim. (Cl. 219—39)

1

This invention relates to an air conditioning apparatus and it is primarily an object of the invention to provide an apparatus of this kind which can be employed with equal facility in either raising or lowering the temperature of the chamber, such as a room of a house or the interior of a closed vehicle.

It is also an object of the invention to provide an apparatus of this kind including a normally enclosed housing partitioned to provide a fan compartment and a discharge compartment, together with a fan within the fan compartment for directing a stream of air from the fan compartment to the discharge compartment and wherein there is provided within the housing between the compartments, means for conditioning the air stream as by either raising or lowering the temperature thereof.

Another object of the invention is to provide an apparatus of this kind wherein a stream of air is caused to flow therethrough and wherein such stream of air has contact with heated surfaces, whereby the air, when vitiated, may be restored.

An additional object of the invention is to provide an apparatus of this kind comprising a housing through which the air to be treated is directed and wherein means are provided for filtering the air before entering the housing and also for again filtering the air after being treated and before leaving the housing.

The invention consists in the details of construction and in the combination and arrangement of the several parts of my improved air conditioning apparatus whereby certain important advantages are attained, as will be hereinafter more fully set forth.

In order that my invention may be better understood, I will now proceed to describe the same with reference to the accompanying drawings, wherein:

Figure 1 is a diagrammatic view and also partly in elevation and partly in section of an air conditioning apparatus constructed in accordance with an embodiment of the invention;

Figure 2 is a horizontal sectional view taken through the upper portion of Figure 1; with the filtering elements diagrammatically illustrated withdrawn;

2

Figure 3 is a view in side elevation of the apparatus as herein embodied;

Figure 4 is a view in top plan; and

Figure 5 is a view in end elevation.

In the embodiment of the invention as disclosed in the accompanying drawings, H denotes a housing of desired dimensions and which is herein disclosed as rectangular in form and of a size to be readily transported to be placed as required as within a room of a building or within the interior of an automobile body. The use of the apparatus forms no particular part of the invention.

The housing H has depending from its corner portions the supporting legs 1. One end portion of the housing H is divided by a partition 2 extending from the bottom wall 3 of the housing H and stopping short of the top thereof leaving an air port 2' thereover.

This partition with the adjacent end wall of the housing provides a fan chamber C at one end of the housing, the top of which is closed by a door 4 herein disclosed as of a swinging type although such door may be of other desired construction.

When the door 4 is in open position, ready access may be had to the fan F within said chamber C. The bottom wall 3' for the chamber C is in the form of a grid for the admission of air which is facilitated by the fact that the legs 1 support the housing H at a desired distance above the surface upon which the housing may be positioned.

Normally disposed over the bottom wall 3' is an air filtering element 5 herein disclosed as of a sliding or drawer type and which can be moved into position across the bottom of the chamber C or withdrawn therefrom through a suitably positioned opening 6 in the front side wall 7 of the housing H.

The upper portion of the partition 2 is provided with the openings 8 whereby the air stream created by the fan F may pass therethrough and which flow of the air stream may be controlled in any conventional manner as by the use of shutters, not shown, to which ready access may be had when the door 4 is in open position.

As herein embodied, the fan F is mounted upon the upper end portion of the vertically disposed drive shaft 11 of an electric motor 12. This motor 12, together with the shaft 11, is supported in the

central portion of the chamber C from the bracket 14 extending inwardly of the chamber C from the rear side wall 15 of the housing H.

The end of the housing H remote from the chamber C is divided by the partition 16 extending from the top of the housing to a point closely adjacent the bottom wall 3 thereof whereby is provided a discharge compartment D to which access is had through the opening 17 afforded by the space between the lower end of the partition 16 and the bottom wall 3.

The front side wall 7 at the upper portion thereof is provided thereacross with the louvers 18 through which passes out air from within the compartment D. The top of this compartment D is closed by a door 19 herein disclosed as of a swinging type although it can, if desired, be otherwise. This door 19, when opened, permits the desired placement within the lower portion of the compartment D of a container 20 for water or Dry Ice.

This container 20 is provided with an upstanding filler spout 21 to permit the ready placement of water or Dry Ice within the container C without necessitating removal of the air filtering element 22. This element 22 is also of a slide or drawer type and is readily insertible within the chamber D or removed therefrom through a proper opening 23 in the front side wall 7 of the housing immediately below the louvers. One corner portion 24 of the air filtering element 22 is cut out in order to allow the spout 21 of the container 20 within the compartment D to extend as desired above the applied filtering element 22.

The top of the housing H between the partitions 2 and 16 is also initially opened but is normally closed by a removable lid or top member 25. Depending from this lid or member 25 at points spaced lengthwise thereof are the baffle plates 26 of metal which are of a length to terminate above the bottom 3. These baffle plates 26 are also positioned centrally between the upstanding baffle plates 27 carried by the bottom wall 3 and terminating below the top of the housing H. One end baffle plate 26 is positioned between the partition 2 and a baffle plate 27 while one of the baffle plates 27 is positioned between the partition 16 and a baffle plate 26.

The baffle plates 26 and 27 coact to provide means whereby the air stream as forced through the housing H by the fan F will travel in a tortuous path and in a manner to have contact with the baffle plates 26 and 27 which, when said baffle plates 26 and 27 are properly heated, will result in altering the physical character of the air in the stream in a desired manner.

Arranged at opposite sides of each of the baffle plates 26 and 27 are batteries of vertically spaced electrical heating units 28 which are supported upon one side wall and provide the requisite means for effecting the heating of the plates 26 and 27 and the air passing through the housing H. In the present embodiment of the invention, these various heating elements 28 are electrically connected through the conductors a with a multi-pole switch 29 adapted to have connection with a source of electrical energy in the usual manner.

This multi-pole switch 29 may be of any type and provides means whereby all or any desired number of the units 28 may be caused to operate. The switch 29 in the present embodiment of the invention is carried by the front side wall 7 which also carries a switch 30 for connection with a suitable source of electrical energy and with which switch 30 is also electrically con-

nected the motor 12 through the conventional conductors b.

When it is desired that the apparatus be employed for cooling the atmosphere, Dry ice may be placed within the container 20 and, of course, the heating elements 28 will be closed off.

The end wall 31 of the housing 11 associated with the compartment D is provided in its upper part with a relatively large opening 32 normally closed by a removable cap 33 or otherwise as may be preferred. This opening 32 provides an outlet which can be readily used should it be desired to couple to the apparatus a flexible tube to conduct the treated air to other localities or should it be desired to use heated air as a windshield defroster.

It is also to be stated that the major portion of the top of the container 20 is open so that when water is placed in the container as the heated air passes through the compartment D over the top of the container, effective humidification of such air will be had.

The bottom wall 33 of the compartment D has depending therefrom a conventional drain cock 34.

From the foregoing description it is thought to be obvious that an air conditioning apparatus constructed in accordance with my invention is particularly well adapted for use by reason of the convenience and facility with which it may be assembled and operated.

I claim:

An air conditioning device of the character stated comprising a housing having top, bottom, 35 end and side walls, vertically disposed transverse partitioning walls within the housing transversely between the side walls and each in spaced relation with an end wall, one of the partitioning walls terminating short of the housing 40 top wall to provide an air passage way, the other partitioning wall terminating short of the housing bottom wall to provide an air passage way, the space between the said one partitioning wall and the adjacent end wall of the housing 45 forming an air admission chamber, the bottom wall at the bottom of said chamber having an air inlet opening, the space between the said other partitioning wall and the adjacent end wall providing an air conditioning chamber, an air outlet 50 means leading from the top part of the air conditioning chamber, said top wall being formed to provide a removable cover at the top of the air conditioning chamber which cover is normally closed during the operation of the apparatus, a 55 receptacle positioned within the air conditioning chamber upon the bottom wall and having spaced relation with the adjacent partitioning wall to provide a vertical air passage way, said receptacle being of materially less height than the air conditioning chamber, the receptacle being open at its top and having an upwardly directed filling neck through which an air humidifying agent 60 may be introduced into the receptacle, a flat filtering unit formed to horizontally partition the 65 air humidifying chamber to cover all of the open top of the receptacle with the exception of the portion defined by the filling neck, said filtering element also covering the upper part of said vertical air passage way, a side wall of the housing 70 having an opening through which said flat filtering element is inserted, heating elements disposed in the housing between said vertical partitioning walls, and means for maintaining an air circulation through the housing from the 75 air admission chamber to the air humidifying

chamber for discharge through the air discharge opening leading from the upper part of the humidifying chamber.

JOSEPH H. SWEENEY.
